ARTICLE-WORKING APPARATUS

Bruno A. Raetsch, Baltimore, Md., assignor to
Western Electric Company, Incorporated, New
York, N. Y., a corporation of New York

Application May 4, 1946, Serial No. 667,345

5 Claims. (Cl. 242—9)

1

This invention relates to article-working apparatus, and more particularly to means for starting windings of resistance wires around supporting cards at particular points on the cards.

In the manufacture of potentiometer cards of a type including a supporting card having a predetermined profile and an extremely fine resistance wire wound closely around the supporting card, it is desirable to begin the winding of the fine resistance wire around the potentiometer card at a predetermined point thereon with respect to the profile thereof. In the past, due to the extreme fineness of the wire and the close winding thereof, it has been difficult to start the winding at a predetermined point with respect to the profile of the supporting card.

An object of the invention is to provide new and improved article-working apparatus.

Another object of the invention is to provide new and improved apparatus for winding a fine insulating wire around a supporting card in a predetermined position with respect to the card.

In accordance with one embodiment of the invention, a supporting card having a profile and holes near the ends thereof in predetermined positions with respect to the profile is held securely by clamps and fixed pins, which pins enter the holes in the supporting card in close fitting relationship therewith. A serving head is mounted on a carriage which is mounted slidably on a lathe bed, and a feed screw serves to move the serving head along the supporting card to wind a resistance wire thereon with a uniform lay. A dial indicator is mounted adjacent to the starting point of the serving head in a fixed position with respect to the supporting card. A spring-loaded plunger is mounted on the carriage in a position in which it actuates the dial indicator when the serving head and the carriage are moved to a position near that at which the winding of a resistance wire is to be begun. When the serving head is in a position in which a winding of a resistance wire upon the supporting card is to be started, the dial indicator will have a predetermined reading, which reading indicates to an operator of the apparatus that the winding may be begun at this position.

A complete understanding of the invention may be obtained from the following detailed description of an apparatus forming a specific embodiment thereof, when read in conjunction with the appended drawings, in which:

Fig. 1 is a fragmentary, top plan view of an apparatus forming one embodiment of the invention;

2

Fig. 2 is a fragmentary, front elevation of the apparatus;

Fig. 3 is an enlarged, vertical section taken along line 3—3 of Fig. 2, and

Fig. 4 is an enlarged, top plan view of a portion of the apparatus.

Referring now in detail to the drawings, an apparatus for winding a resistance wire 10 (Fig. 1) having a very small diameter around a supporting card 11 to form a potentiometer card 12 is shown therein. This winding apparatus per se is disclosed and claimed in Patent No. 2,382,451, issued October 14, 1945, and includes a serving head 15, which is mounted in a predetermined position on a carriage 16, which may be moved along a lathe bed 17 by a feed screw 18. The winding apparatus also includes clamps 19 and 20 having fixed pins 21 and 22, respectively, which fit tightly within bores formed in the supporting card 11, of which a bore 23 is shown, to hold the card in a position in which a corner 25 and a lobe 26 of the card are positioned predetermined distances from the pin 21.

A high-sensitivity dial indicator 30 (Fig. 4) of a well-known type and having a spring-loaded plunger 31, a pointer 32 and a dial 33 calibrated in thousandths of an inch is mounted on a support 35 in a predetermined position with respect to the pin 21, in which position the tip of the spring-loaded plunger 31 normally is a predetermined distance to the left of the pin 21, as viewed in Fig. 2, and the plunger 31 extends parallel with the lathe bed.

A bracket 40 having arms 41—41 having bores 42—42 (Fig. 3) formed therein serves to mount an externally threaded guide 45 in the bores 42—42. A knurled nut 46 fitting closely but rotatably between the arms 41—41 of the bracket 40 is threaded upon the guide 45. Knurled nuts 46 and 47 threaded on the guide 45 hold the guide in a fixed position with respect to the bracket 40. The nuts 46 and 47 may be threaded farther onto or farther off of the guide 45 to adjust the position of the guide with respect to the bracket 40 and hence with respect to the serving head 15. The guide 45 has a bore 50 formed therein and also is provided with a counterbore 51. A carriage plunger 52 is mounted slidably within the bores 50 and 51, and has a shoulder 55 formed thereon. A compression spring 56 positioned in the counterbore 51 in the guide 45 urges the plunger 52 to the left, as viewed in Fig. 3, and the movement of the plunger 55 to the left is limited by a collar 57 fastened to the right end of the plunger.

The bracket 40 is provided with holes 60—60,

in which a gauge rod 61 is slidably mounted. A pointer 62 inscribed on the bracket indicates on a scale 63 formed on the gauge rod 61 the normal position of the gauge rod with respect to the serving head 15. An adjustable stop 65 mounted adjustably on an arm 66 formed on the guide 45 is designed to engage the end of the gauge rod 61 to position the guide 45 with respect to the gauge rod and the bracket 40. The stop 65 is pinned to prevent adjustment thereof after it has been adjusted correctly initially. When the stop 65 is in engagement with the gauge rod, the position of the guide 45 with respect to the serving head 15 may be determined from the reading of the pointer 62 on the scale 63 of the gauge rod. A locking pin 67 is slidably mounted in a bore 70 formed in the bracket 40, and is designed to enter one of a plurality of bores 71-71 formed in the gauge rod 61 to secure the gauge rod in one of several possible positions thereof with respect to the bracket 40 and the serving head 15.

The position of the pointer 62 with respect to the serving head 15 is known, and the normal position of the tip of the plunger 31 of the indicator 30 with respect to the pin 21 is known. The distance from the left end of the stop 65 to the left end of the carriage plunger 52 also is known. The gauge rod 61 is calibrated in starting positions for different types of cards, and the nuts 46 and 47 are actuated to move the guide to a position in which the stop 65 engages the gauge rod 61. The distance from any mark on the gauge rod 61 to the right end thereof also is known. Hence, for any particular setting of the gauge rod and guide 45, in which setting the stop 65 engages the gauge rod, the distance parallel to the lathe bed 17 from the left end of the gauge rod to the serving head is known, and this distance remains fixed until a further adjustment of the gauge rod and the guide 45 are made. Since the normal distance from the pin 21 to the tip of the plunger 31 and the distance from the left end of the carriage plunger 52 to the serving head 15 are known, the distance from the serving head to the pin 21 is known when the plunger 52 just touches the plunger 31. Hence, any further movement of the serving head 15 to the left is indicated by the dial indicator 30.

In the operation of the apparatus described hereinabove, the supporting card 11 (Figs. 1 and 2) is thrust partially through the serving head 15, is placed over the pins 21 and 22 and is clamped by the clamps 19 and 20 in a position in which the pins 21 and 22 project through the bores illustrated by the bore 23, in close-fitting engagement therewith so that the supporting card is held in a predetermined position with respect to the dial indicator 30. The serving head 15 then is moved to the left, as viewed in Fig. 1, by the feed screw 18 and the carriage 16. As the carriage approaches the position at which the winding of the resistance wire 10 around the supporting card is to be started, the carriage plunger 52 engages the spring-loaded plunger 31 and urges it to the left. The spring 56 is much stronger than the spring urging the plunger 31 to the right and is normally under a high enough compression that the carriage plunger 52 is not moved against the action of the spring 56 until the spring urging the plunger 31 to the right is completely compressed. On further movement, the spring 56 will be compressed to prevent damage to the indicator.

The movement of the spring-loaded plunger 31

to the left moves the pointer 32 from the zero point on the dial 33 in proportion to the linear distance the plunger 31 is moved by carriage plunger 52, and when the pointer 32 is in a predetermined position with respect to the dial 33, the serving head 15 is in the correct position with respect to the corner 25 and the lobe 26 of the supporting card 11, the corner 25 and the lobe 26 to begin winding the fine resistance wire 10 upon the supporting card. The indicator also indicates when the serving head 15 is winding particular turns of the resistance wire positioned near the initial turn thereof on the card so that the machine may be stopped and these turns marked for future operations thereon.

The dial indicator 30 is highly sensitive so that the position of the serving head 15 with respect to the supporting card 11 may be determined within very close limits. Hence, the winding of the resistance wire 10 around the supporting card 11 may be started at a very accurately located position with respect to the corner 25 and the lobe 26 of the supporting card so that potentiometer cards, illustrated by the potentiometer card 12, may be made uniformly. The carriage plunger 52 is resiliently rather than rigidly mounted on the carriage 16 so that damage to the indicator from too great movement to the left of the carriage is prevented, but the spring 56 is strong enough and is compressed enough initially that the indicator will be actuated to read its full range before the spring 56 will be further compressed.

What is claimed is:

35. 1. An apparatus for winding potentiometer cards, which comprises a lathe bed, means for clamping an insulating card at the ends thereof in a predetermined position extending along the lathe bed, a serving head for winding a wire around an insulating card held by the card-holding means, a carriage mounted on the lathe bed for supporting the serving head, a feed screw for reciprocating the carriage along the lathe bed to reciprocate the serving head along the insulating card, a spring-loaded plunger carried by the carriage, and a dial indicator mounted in a predetermined position with respect to the insulating card and engageable by the spring-loaded plunger for indicating the position of the serving head with respect to the insulating card.
40. 2. An apparatus for winding potentiometer cards, which comprises a guideway, means for clamping an insulating card at the ends thereof in a predetermined position extending along the guideway, a serving head for winding a wire around an insulating card held by the card-holding means, a carriage slidably mounted on the guideway for supporting the serving head, a feed screw for advancing the carriage along the guideway to advance the serving head along the insulating card, a spring-loaded plunger carried by the carriage, and a dial indicator at one end of the guideway in a predetermined position with respect to the insulating card and engageable by the spring-loaded plunger for indicating the position of the serving head with respect to the insulating card when the carriage is moved to a position near that end of the guideway.
45. 3. In a winding apparatus including a lathe bed, means for holding an insulating card in a position extending along the lathe bed and in a predetermined relative longitudinal position with respect to the lathe bed, a serving head, a carriage for mounting the serving head and a feed

screw for moving the carriage along the lathe bed to move the serving head along an insulating card held by the card-holding means, means for indicating the starting position of the serving head with respect to the insulating card comprising a spring-loaded plunger mounted on the carriage and movable therewith along a predetermined path, and a dial indicator including a movable plunger positioned in said path in alignment with the first-mentioned plunger and engageable thereby for indicating the position of the serving head with respect to the insulating card when the first-mentioned plunger engages the movable plunger of the indicator.

4. In a winding apparatus including a guideway, means for holding an insulating card in a predetermined position with respect to and parallel with the guideway, a serving head for winding a fine resistance wire around an insulating card held by the card-holding means, a carriage mounted for movement along the guideway for holding the serving head and a feed screw for advancing the carriage along the guideway to move the serving head along the insulating card, a device for indicating the position of the serving head with respect to the insulating card comprising a gauge including a pointer, a dial, and a movable plunger for moving the pointer along the dial, said gauge being mounted in a predetermined position with respect to the insulating card, a bracket mounted on the carriage, a guide supported adjustably on the bracket, a spring-loaded plunger carried by the guide, and means for indicating the normal position of the last-mentioned plunger with respect to the bracket, said last-mentioned plunger being mounted in a position in which it engages the first-mentioned plunger near an end of the path

of travel of the carriage so that the pointer indicates on the dial the position of the serving head with respect to the insulating card when the carriage is near that end of its path of travel.

5. An apparatus for winding potentiometer cards, which comprises a guideway, means for clamping an insulating card in a predetermined position extending along the guideway, a serving head for winding a wire around an insulating card held by the card holding means, a carriage slidably mounted on the guideway for supporting the serving head, means for advancing the carriage along the guideway to advance the serving head along the insulating card, an actuator carried by the carriage, and a dial indicator at one end of the guideway in a predetermined position with respect to the insulating card and engageable by the actuator for indicating the position of the serving head with respect to the insulating card when the carriage is moved to a position near that end of the guideway.
